BY *James V. Ramsey*

ATTORNEY

UNITED STATES PATENT OFFICE.

ISAAC H. CARR, OF CINCINNATI, OHIO.

AUTOMATIC GAS-SHUT-OFF VALVE.

Application filed August 21, 1922. Serial No. 583,214.

To all whom it may concern:

Be it known that I, ISAAC H. CARR, a citizen of the United States, residing at Cincinnati, in the county of Hamilton and State of Ohio, have invented certain new and useful Improvements in Automatic Gas-Shut-Off Valves, of which the following is a specification.

My invention relates to safety means in the use of combustible gases.

Where the ordinary types of valves are used serious accidents are caused by the supply of gas being temporarily interrupted and thereby extinguishing the flame so that when the supply is resumed the gas is not consumed but pervades the building in which the device is located, forming a dangerous explosive mixture with the air and also subjecting persons in the building to asphyxiation especially where natural gas is used, as it has practically no perceptible odor whereby its presence is detected.

The objects of my invention are to provide a simple, efficient and durable means for automatically shutting off the flow of gas or fluid under pressure when pressure is reduced below normal or no longer exists thereby providing safety means to prevent explosion, suffocation or asphyxiation due to the temporary stoppage in the flow of gas which extinguishes the flame so that when pressure is resumed the gas is prevented from escaping into the rooms where it would cause probable dangerous results.

It also serves to regulate the amount of gas supply to the device; provides means to compel the manual restoration of the valve to open position when the gas pressure is restored; insures the absolute cutting off of the gas when pressure in the source of supply no longer exists; provides means whereby foreign matter is automatically removed from the valve seat and serves to economize in the use of gas and to keep the stove or furnace free from gas, when for any reason, the flame has been extinguished.

An advantage of my invention is the safety afforded, as for instance, when the gas in the stove is unwittingly turned on by a child.

My invention consists in means whereby the above objects are accomplished and in the construction, combination and arrange-

ment of parts as herein set forth and claimed.

In the drawings:

Fig. 1 is a side elevation of the valve showing it in open position;

Fig. 2 is a plan view thereof;

Fig. 3 is an end view;

Fig. 4 is a vertical section on the line 4—4 of Fig. 2;

Fig. 5 is a perspective view of the supply valve;

Fig. 6 is a perspective view of the by-pass valve;

Fig. 7 is a perspective view partly broken away of the primary inverted cup shaped floating valve and secondary conical valve with connecting parts;

Fig. 8 is a perspective view showing the inlet valve open and the by-pass valve closed in position for the gas to pass therethrough;

Fig. 9 is a perspective view of the lock washer; and

Fig. 10 is a plan view of the device with supply valve in set position and with cap and interior parts removed.

In the embodiment of my invention as illustrated and which shows a preferred construction I provide a safety valve body 1 having an integrally formed inlet connection 2 and an integrally formed outlet connection 3. The valve body is provided in its top with a circular space 4, and extending downwardly therefrom I provide a cylindrical valve chamber 5 having grooved passages 6 in its wall extending from space 4 downwardly in valve chamber 5. Immediately below said valve chamber is formed a threaded opening 7 in which a threaded cylindrical bearing 8, having central vertical opening 9, is screwed. Immediately below said bearing is a secondary cylindrical valve chamber 10 and below said valve chamber is a cylindrical outlet 11 of less diameter than said valve chamber whereby a sharp or angular circular valve seat 12 is formed. A gas passage 13 extends from space 4 downwardly into the secondary valve chamber near its top. By-pass 14 extends from said passage to gas outlet 3 and is provided with valve 15. The upper end of safety valve body 1 is externally screw threaded to receive screw threaded cap 16 on rubber gasket 17 to securely close the same.

The primary safety valve is preferably

formed of aluminum or other light material in the shape of an inverted cup 18 with a hole 19 centrally through its upper closed end. Stem 20 having cone secondary valve 21 on its lower end extends upwardly through said opening 9 and hole 19 and said primary valve is held in adjusted position thereon by conical nuts 22 and 23 having threaded engagement with said stem, there-
10 by permitting some play of said primary valve upon said stem to adapt it to move freely and not bind against the wall of the primary valve chamber. Supplemental conical nut 24, as shown in Fig. 7, may be used if
15 desired to lock nut 22 in position. The lower end of stem 20 is seated in bearing 8 and its upper end is seated in socket 25 of screw threaded cap 16 and said stem is adapted to freely move up and down in said
20 bearing and socket when said valves are moved. Conical valve 21 is adapted to form a close fit with its seat 12 and possesses the advantage of readily dislodging any foreign substances which may lodge thereon. It also
25 adapts itself to continuous perfect seating notwithstanding any wear of the parts. In-
30 let connection 2 is provided with gas inlet 26 extending from its threaded end 27 to primary cylindrical valve chamber 5 shortly
35 below the lower ends of grooved passages 6 and it is also provided with a resetting gas inlet 28 extending from said threaded opening to said primary valve chamber below said gas inlet 26. Inlet connection 2
40 is provided with tapered opening 29 extending transversely therethrough to receive spigot or valve plug 30 having gas passages
31 and 32 extending transversely there-
45 through in different directions. Said spigot is provided with operating handle 33 and with stop 34 to limit its open or closed position. It is secured in position by nut 35 upon its threaded end, said nut bearing upon interposed lock washer 36.

50 The several parts are assembled in the positions clearly shown in full lines in Fig. 4 and is interposed in the gas connection leading from the source of gas supply to the stove or furnace. When thus connected and in the position shown by full lines in Fig. 4 the gas will pass through gas inlet 26, primary cylindrical valve chamber 5, grooved passages 6, passage 13, secondary valve chamber 10 and cylindrical outlet 11, 55 the pressure of the gas causing said primary valve to remain suspended in the upper end of said valve chamber and the secondary valve to be unseated whereby the gas is permitted to escape upwardly through the lower ends of said grooves and discharge through outlet 3 to a burner in a stove or furnace. When, however, the pressure becomes weak or the flow of gas is temporarily interrupted said primary valve will drop by gravity to
60 the point indicated by dotted lines in Fig.
65

4 and will carry with it said cone valve 21 forcing it upon seat 12 thereby closing the safety cut-off by both the primary and secondary valves and should the gas pressure be resumed it will be securely closed against 70 passage therethrough by both the primary and secondary valves.

In order to reset the device for the continual flow of gas therethrough it is only necessary to turn the spigot to "set position," so that the transverse passage 31 will coincide with resetting gas inlet 28 whereupon the gas will enter primary valve 18 in its dotted position, Fig. 4, thereby forcing it upwardly as soon as by-pass valve 14 has 80 been momentarily turned to open position to permit the escape of any residual gas above said primary and secondary valves.

Then turn the spigot to "on position," as shown in Figs. 1, 2 and 4 thereby closing resetting gas inlet 28 and opening gas inlet 26 thus restoring the device to its operative position for the regular passage of gas therethrough under normal conditions and until the primary and secondary valves are again 90 closed due to insufficient gas pressure or temporary stoppage in the flow of gas.

My safety gas cut-off is extremely simple, compact and of economical construction and is adapted to effectually perform the desired 95 functions.

While I have shown and described a particular construction and arrangement of parts it will be apparent that it is capable of some modification without departure from 100 its scope or spirit as defined in the claims.

What I claim as new and desire to secure by Letters Patent is:

1. In an automatic gas shut-off valve, a valve body having a primary valve chamber 105 and a secondary valve chamber therebelow, said valve body having a space in its upper end and grooves in the upper end wall of said primary valve chamber communicating with said space and having a passage leading from said space into said secondary valve chamber, a primary floating valve in said primary valve chamber, a secondary valve in said secondary valve chamber, a vertical slideable stem on which said primary and secondary valves are mounted, said valve body having a gas inlet below said grooves and a resetting gas inlet below said first named gas inlet, a valve adapted to open and close said inlets, said valve body 115 having a discharge outlet and a by-pass leading from the passage to said discharge outlet, and means to open and close said by-pass, substantially as set forth and for the purposes specified.

2. In an automatic gas shut-off valve, a valve body having a primary valve chamber and a secondary valve chamber therebelow having a sharp edged circular seat and having a passage forming communication be- 130

tween said valve chambers, a primary floating valve in said primary valve chamber, a secondary cone valve in said secondary valve chamber adapted to rest upon said sharp 5 edged circular seat, a vertical slidable stem on which said primary and secondary valves are mounted, said valve body having a gas inlet below the outlet of said primary valve chamber and a resetting gas inlet below said 10 first named gas inlet, a valve adapted to simultaneously open one of said inlets, while closing the other inlet, said valve body having a discharge outlet and a by-pass leading from said passage to said discharge outlet, 15 substantially as set forth and for the purposes specified.

3. In an automatic gas shut-off valve, a valve body having a primary valve chamber and a secondary valve chamber therebelow, 20 said primary valve chamber having a grooved outlet and said valve body having a space above said primary valve chamber with which said grooved outlet communicates and having a passage leading from 25 said space into said secondary valve chamber, a primary inverted cup shaped loosely mounted floating valve in said primary valve chamber, a secondary valve in said secondary valve chamber supported by said primary 30 valve, a vertical slidable stem on which said primary and secondary valves are mounted, a gas inlet below the gas outlet in said primary valve chamber, a resetting gas inlet below said first named gas inlet and a valve adapted to open and close said gas 35 inlets, substantially as set forth and for the purposes specified.

4. In an automatic gas shut-off valve, a valve body having a primary valve chamber and a secondary valve chamber, said primary valve chamber having a grooved outlet and said valve body having a space above said primary valve with which said grooved outlet communicates and having a passage 45 leading from said space into said secondary valve chamber, a floating valve in said primary valve chamber, a cone valve in said secondary valve chamber, a vertical slidable stem on which said floating and cone valves 50 are mounted, a resetting gas inlet below said first named inlet, and a valve adapted to open and close said gas inlets, substantially as set forth and for the purposes specified.

5. In an automatic gas shut-off valve, a valve body having a primary valve chamber and a secondary valve chamber and having a passage connecting said chambers, a primary inverted cup shaped tilting floating valve in said primary valve chamber, a secondary valve in said secondary valve chamber supported by said primary valve, 60

a gas inlet below the gas outlet in said primary valve chamber, a resetting gas inlet below said first named gas inlet and means to control the flow of gas through said gas 65 inlets, substantially as set forth and for the purposes specified.

6. In an automatic gas shut-off valve having a primary valve chamber and a secondary valve chamber arranged below said primary valve chamber and having a passage leading from said primary valve chamber to said secondary valve chamber, an inverted cup shaped valve in said valve chamber, a secondary valve in said secondary 75 valve chamber, a stem supporting said secondary valve and adjustably attached to said primary valve, a gas inlet, a resetting gas inlet below said first named gas inlet, a valve adapted to open and close said gas 80 inlets, respectively.

7. In an automatic gas shut-off valve having a primary valve chamber and a secondary valve chamber with a passage leading from said primary valve chamber to said secondary valve chamber, a primary valve in said primary valve chamber, a secondary valve in said secondary valve chamber, a threaded stem to which said primary valve is attached and extending through said primary valve and tapered nuts secured above and below said primary valve whereby said valve is adapted to be adjusted therein relative to said secondary valve and whereby said primary valve is adapted to be tiltably 90 mounted thereon to permit it to move freely in said primary valve chamber without binding.

8. In an automatic gas shut-off valve, a valve body having a primary valve chamber and a secondary valve chamber therebelow, 100 said primary valve chamber having a grooved outlet and said valve body having a space above said primary valve chamber with which said grooved outlet communicates and having a passage leading from 105 said space into said secondary valve chamber, a primary floating valve in said primary valve chamber, a secondary valve in said secondary valve chamber, a vertical 110 slidable stem on which said primary and secondary valves are mounted, said valve body having a gas inlet below said grooved outlet and a resetting gas inlet below said first named gas inlet, a valve adapted to 115 simultaneously open and close said inlets, said valve body having a discharge outlet, and a valved by-pass leading from said passage to said discharge outlet, substantially as set forth and for the purposes specified.

ISAAC H. CARR.
